LEONARD DOUGLAS HAMMON, OF BAY OF PLENTY, AND DAVID WILLIAM MCGILL AND HAROLD BARTLE IRVINE, OF CHRISTCHURCH, NEW ZEALAND.

THERMOSTATIC SWITCH.

Application filed June 6, 1922. Serial No. 566,352.

To all whom it may concern:

Be it known that we, LEONARD DOUGLAS HAMMON, DAVID WILLIAM MCGILL, and HAROLD BARTLE IRVINE, all subjects of the

5 King of Great Britain, residing at King Street, Opotiki, in the Bay of Plenty, in the Dominion of New Zealand, 251 Edgeware Road, Christchurch, in the Dominion of New Zealand, and 34 Latimer Square, 10 Christchurch, aforesaid, respectively, have invented new and useful Improvements in Thermostatic Switches, of which the following is a specification.

This invention relates to electrically 15 heated irons of all kinds and may if desired be applied also to other forms of electrically heated apparatus, the object of the present invention being to provide means whereby the electric circuit in which the heating 20 element is contained, may be automatically thrown open upon the temperature of such iron or other appliance rising to a predetermined degree, thus avoiding the dangerous consequences of overheating.

25 In carrying this object into effect the present invention consists briefly of the provision of a switch inserted in the circuit containing the heating element such switch being adapted to be opened so as to break the said circuit by the operation of an electro-magnetic device the winding of which is included in a relay circuit consisting in the preferred form of the invention of a shunt off a portion of the heating element, the opening and closing of such relay circuit being effected by the operation of a thermostatic element in response to variations of temperature produced by the said heating element.

40 The said thermostatic element is necessarily mounted within or upon the structure of the iron or other heating appliance so as to be subject to the thermal influence thereof, while the switch controlling the 45 main circuit, that is to say the circuit containing the heating element, may, together with its said electro-magnetic controlling device be arranged either upon the said structure or mounted separately as upon a 50 wall or other fixture, in which case the flexible cord for connecting the iron or appliance with the current will contain leads for both the main and relay circuits.

In order that the nature of the invention 55 and its construction may be clearly under-

stood, reference will now be made to the accompanying sheet of drawings in which:—

Fig. 1 is a longitudinal section through an iron equipped in accordance with the present invention and in which an appropriate position for the switch, if the latter is mounted upon the iron, is indicated in dotted lines, 60

Fig. 2 is a diagram of the wiring employed in cases where the switch adapted to open and close the main circuit is mounted upon the iron, 65

Fig. 3 is a perspective view showing one practical embodiment of the magnetically operated switch employed to control the main circuit, the cover and a portion of the frame being broken away to clearly display the internal parts, 70

Fig. 4 is a longitudinal section of the solenoid shown in Fig. 3, and,

Fig. 5 is a diagram of the wiring employed in cases where the said switch is not mounted upon the iron, 75

As here shown the invention is applied to an ordinary well known form of electrically heated iron comprising a base portion 1 containing a resistance or element 2 (Figs. 2 and 5), adapted to be heated by the passage therethrough of electric current supplied by means of a main circuit 3, connecting with a suitable source, 80

To complete the structure the said base is surmounted by a hollow body or cover 4, upon which is carried a suitable handle 5, by means of which the iron is manipulated when in use, 85

According to the present invention in the circuit 3, is inserted a switch 6 which may be of any suitable form and adapted, when in the closed condition, to complete such circuit and so supply current to the element 2 and when in the open condition to break such circuit. The said switch is provided with a handle 7 or other means whereby it may be opened or closed by hand, 90

Mounted adjacent to the said switch is a 100 magnetically operated device adapted when energized to carry such switch into its said open position.

As here shown this device takes the form of a solenoid consisting of a stationary 105 winding 8 in the axis of which is slidably arranged an iron core 9 connected by means of a connecting-rod 10 with the operable member of the switch, the arrangement being such that upon a current being passed 110

through the winding 8 the attraction by the latter of the core 9 will effect the opening of the said switch.

In order to increase this attraction the 5 winding 8 is preferably encased within an iron shell 11 extending around the periphery and one end of such winding while the core 9 is provided with an iron disc or plate 12 adapted to approach or come in contact 10 with the open end of said shell when the said movement of the core within the winding takes place.

Suitable means are preferably provided 15 for the purpose of limiting the outward movement of the core 9 away from the winding 8. As here shown such means comprise lugs or the like 13, formed upon the exterior of the shell 11 and into which lugs are tapped screws 14. By this arrangement 20 the screws 14 may be so adjusted that their heads will come in contact with the plate 12 when the latter is in its outward position from the winding 8 thereby limiting the extent of such outward movement.

25 The said winding 8 is inserted in series in a relay circuit 15 which, in the preferred form of the invention, consists, as here shown, of a shunt tapped off the main circuit 3 and from the position in such circuit 30 to the inner or "dead" side of the switch 6 in order that the current may be disconnected from the relay circuit when such switch is open.

In the preferred form of the invention 35 also one lead of such relay circuit is tapped off the heating element itself at a desired point upon the length thereof thereby enabling a portion of such element to be utilized as a resistance whereby the line voltage 40 supplied to the main circuit is broken down to a lower potential as desirable for use in the relay circuit.

For the purpose of controlling the opening and closing of the relay circuit as required for the operation of the invention, a 45 thermostatic element 16 is provided and arranged within the cavity of the cover 4 or at some other portion upon the iron-structure where it will be subject to the heat produced by the heating element 2, such thermostatic element being adapted to operate make-and-break contacts arranged in series 50 in the relay circuit.

The said thermostatic element consists 55 preferably as here shown of a bi-metallic strip, that is to say a strip composed of two metals having different coefficients of expansion and attached together side-by-side through-out the length of such strip in order 60 that the latter will as a whole possess the property of warping or bending in one direction or the other as its temperature rises and falls.

The said strip is rigidly attached at one 65 end as by means of a screw 17 to the iron

structure but is insulated electrically therefrom, while the other end of such strip is free to move in an upward and downward direction when its said warping action takes place.

70 Arranged adjacent to the said free end of the strip is a terminal 18, insulated electrically from the iron structure and having a contact point 19 with which a contact point 20 upon the said free end of the strip is adapted to make or break electrical connection as such strip warps in response to a rise or fall of temperature.

75 The said contacts 19 and 20 are arranged in series with the relay circuit 15 by connecting one end of the latter to the terminal 18 and the other end of the strip 16.

80 Means of adjustment are also provided in order to enable the said contacts to be set to close the relay circuit when a desired degree of temperature has been reached. As here shown the said means consists of a screw 21 tapped through the terminal 18 and upon the end of which screw is carried the contact 19, thus by turning the said screw in one direction or the other the said contact 19 will be caused to approach or recede from the contact 20.

85 As previously mentioned the switch 6 and its electromagnetic device may be either mounted upon a convenient portion of the iron structure such, for example, as the position 22 indicated in dotted lines in Fig. 1, or the said devices may be mounted 90 separate from the said structure upon a wall 100 or other convenient fixture.

95 In cases where the switch 6 and its controlling electro-magnetic device are mounted upon the iron, or other heating appliance to which the invention is applied such iron or appliance will be provided with a plug or other means of connection having two contacts or terminals 23 and 24 to connect the 105 main circuit to a two-wire flexible cord or the like communicating with the current supply as customary.

110 In cases where the said switch and its controlling electro-magnetic device are mounted separately from the iron or appliance to which the invention is applied the said plug or means of connection is provided, in addition to the said contacts or terminals 23 and 24, with a third contact or terminal 25 and a corresponding three-wire cord or connection 115 26 is provided in order that current from the supply may be conveyed through the switch 6 by means of the terminals 23 and 24 to the heating element, while the portion of the relay circuit extending between the separately mounted portion of the 120 apparatus and that mounted upon the iron is connected by means of the terminal 25.

125 In either form of the arrangement the operation is as follows:—

130 The thermostatic element, as previously

- explained, normally assumes such a position as to separate the contacts 19 and 20 thereby placing the relay circuit 15 in open condition, the electro-magnetic device will therefore 5 fore be inoperative while such conditions obtain. Upon the switch 6 being closed by hand the main circuit 3 will be completed thereby causing current to flow through the heating element 2 which latter will therefore 10 serve to heat the iron. As the temperature of the iron increases it will have the effect of causing the thermostatic element 16 to warp in such a direction as to carry the contact 20 towards the contact 19 which action results, 15 at a predetermined temperature of the iron, in the establishing of electrical connection between such contacts. This connection of the contacts serves to complete the relay circuit thereby causing current to flow through 20 the coil 8 which therefore becomes energized and attracts the core 9 which latter through the connecting rod 10 serves to open the switch 6 and so interrupt the flow of current in the main circuit. 25 If the switch is again closed by hand while the iron remains at the said predetermined temperature, the said means will immediately open such switch.
- As the temperature of the iron falls however, the thermostatic element 16 will gradually return to its normal condition thereby separating the contacts 19 and 20 and so again opening the relay circuit and rendering the electro-magnetic device inoperative. 30
- 35 We claim:
1. A device of the class described, comprising, in combination, a main circuit, a switch in said circuit, electrically operated means for opening said switch, a heating element in said circuit, a thermostatic device within the influence of said heating element, a normally open switch in the circuit of said electrically operated means, said thermostatic device being adapted when heated to a predetermined temperature to close said last 40 switch thereby to direct a current through said electrically operated means and cause the same to open the main circuit, and means for retaining said circuit open.
  2. A device of the class described, comprising, in combination, a main circuit, a switch in said circuit, electrically operated means for opening said switch, a heating element in said circuit, a thermostatic device within the influence of said heating element, 50 a normally open switch in the circuit of said electrically operated means, said thermostatic device being adapted when heated to a predetermined temperature to close said last switch thereby to direct a current 55 through said electrically operated means and cause the same to open the main circuit, means for retaining said circuit open and means for manually closing said circuit.
  3. A device of the class described, comprising, in combination, a main circuit, a switch in said circuit, an electromagnet for opening said switch, a normally open relay circuit tapped off said main circuit for supplying current to said electromagnet, a heating element in the main circuit, a thermostatic device in said relay circuit within the influence of said heating element and adapted to close the relay circuit when heated to a predetermined temperature thereby to energize said electromagnet and open the main circuit, and a lever pivotally connected to said main switch and to the core of said magnet and adapted to hold the switch open after operation of the electromagnet, said lever being manually operable into switch-closing position. 70
